(74) Attorney, Agent, or Firm — Carol N. Green, Esq.

(57) **CLAIM**

The ornamental design for a portable device for remotely transmitting an alert, as shown and described.

DESCRIPTION

FIG. 1 is a top perspective view of the invention.

FIG. 2 is a bottom perspective view of the invention.

FIG. 3 is a front elevation view of the invention.

FIG. 4 is a rear elevation view of the invention.

FIG. 5 is a left elevation view of the invention.

FIG. 6 is a right elevation view of the invention.

FIG. 7 is a front view of the invention.

FIG. 8 is a rear view of the invention.

FIG. 9 is a top perspective view of the invention in use as attached to a keychain; and,

FIG. 10 is a bottom perspective view of the invention in use as attached to a necklace.

The broken lines in FIGS. 9 & 10 showing the invention in use are included for purposes of illustrating environment and form no part of the claimed design.
